PIANO-FORTE ACTION.

T. P. CARR.

UNITED STATES PATENT OFFICE.

THADDEUS P. CARR, OF YELLOW SPRINGS, OHIO.

IMPROVEMENT IN PIANO-FORTE ACTIONS.

Specification forming part of Letters Patent No. 179,397, dated July 4, 1876; application filed April 17, 1876.

To all whom it may concern:

Be it known that I, THADDEUS P. CARR, of Yellow Springs, Greene county, Ohio, have invented a new and useful Piano-Action, of which the following is a specification:

My invention relates to that class of devices commonly known as "repeating piano-actions," and my improvement comprises a novel application of the back catch or stop, that arrests the hammer after the latter has recoiled from the wire.

Heretofore these catches have been either rigidly attached to the key, or else constructed in such a manner as not to sustain the entire weight of the hammer until the jack re-engages with the knuckle, which arrangement renders the action either non-repeating, or too complicated for practical use. I entirely overcome these objections by securing the back-catch to a bearing that is pivoted to the key, said bearing being operated on by the toe of the jack, so as to cause the back-catch to follow the hammer very closely, and arrest the latter with the utmost promptness at any desired distance, after it has recoiled from the wire, and sustaining it in such position until the jack has re-engaged with the knuckle, as hereinafter more fully described.

In the annexed drawings, Figure 1 is a vertical section through a piano-action embodying my improvements, the various operative parts being shown in their normal positions. Fig. 2 is a similar section, but showing the position the various parts assume immediately upon the recoil of the hammer from the wire, said hammer being represented as supported by the back-catch. Figs. 3 and 4 are diagrams representing modifications of the invention.

A represents a portion of the bed-plate or base of a piano-action, which plate is provided with the customary bearing B, that has the key C applied to it in the usual manner. The inner end of this key is gained or notched at c, to receive a block, D, that is attached to said key by screw E. The rear end of said block is furnished with a pivot, d, that supports the back-catch bearing F, whose inner end is slotted at f, to allow free passage of the screw-threaded stem H, which projects rigidly from the upper side of key C. This stem is furnished with two adjustable and cushioned

stops or buttons, h h', for limiting the vertical vibration of said pivoted bearing F. Hinged to this bearing at i is a lever, I, whose front end is traversed by the regulating-screw J, the latter being tapped into the short arm K of said bearing F. L is a spring that maintains lever I in contact with the head of screw J. Attached to bearing F, between slot f and pivot i, is a rod, M, that carries the customary cushioned back-catch m. N is the jack-bearing, attached to key C by regulating-screws n n'. The jack O is pivoted to this bearing at o, and is provided with the customary rearwardly-projecting toe P. Extending from jack O to bearing N is a spring, Q, which has a constant tendency to draw the free end of said jack under the knuckle R, the latter being pivoted at s to butt-block-S. This butt-block is secured to the hammer-rail T. Projecting rearwardly from knuckle R is a shaft, U, secured to the shank v of hammer V. W is the regulating-rail, having a vertical aperture, w, in it, and a notch or cove, w', in its front edge. This rail is traversed with the customary screw X, against whose pad, x, the toe P of jack O strikes when the rear end of key C is elevated. t is a notch in the front edge of rail T, to facilitate the adjustment of jack-bearing N n n'. Y is the wire or string, and Z is a cushion for the rear end of key C to rest on when not in use.

The operation of my action is as follows: When the key C is at rest, its rear end is supported upon cushion Z, while the downward movement of the slotted end of bearing F is limited by the button h. In this position of the key the back-catch m is not in contact with hammer-shank v; neither does the toe P bear against the lever I or pad x. When the rear end of key C is elevated, the front end of lever I is at once brought in contact with toe P, which latter exerts sufficient pressure upon said lever to cause its rear end to rise gradually as far as the button h' will permit. This elevation of the rear end of bearing F compels the back-catch m to follow the hammer very closely, but without coming in actual contact with its shank v. The further elevation of the rear end of key C brings the toe P in contact with stop x, thereby disengaging jack O from knuckle R, and causing hammer V to strike

string Y and recoil therefrom, when the hammer shank v immediately cushions upon back-catch m. This back-catch now supports the entire weight of the hammer, and will continue to do so until the key is allowed to rise slightly under the performer's finger. The moment this happens spring Q draws jack O upward, thus re-engaging the latter with knuckle R, and enables another blow to be instantly struck. When the performer strikes a very hard blow, the hammer recoils from the string Y with such force as to cause the pivoted bearing F to be depressed against button h. The strength of spring L will now support the hammer in this position until the key rises slightly and allows jack O to again re-engage under knuckle R.

By properly regulating the adjusting devices h, h', J, and x, the movements of the various parts may be so timed with reference to each other as to render the catch m effective as soon as the hammer has recoiled far enough to prevent "blocking" the strings. The perforation w enables the adjustment of screw J, while notch w' allows the screw E to be regulated.

As the back-catch bearing, operated by the

toe of the jack, is the principal feature of my invention, I reserve the right to modify the construction of said bearing to suit circumstances. One modification is seen in Fig. 3, where a long plate-spring, L', is substituted for the bent spring shown in Figs. 1 and 2. In Fig. 4, a coiled spring, L'', is employed; but in both of these modifications the action is essentially the same, although the position of the pivot with reference to bearing F is changed.

I claim as my invention—

1. The back-catch M m, rigidly secured to pivoted bearing F d of key C, which bearing is operated by toe P of jack O, substantially as described.
2. The combination of key C, pivoted bearing F f i d, stem H h h', lever I, spring L, jack O P Q, and adjusting devices J X x, as and for the object stated.

In testimony of which invention I herenunto set my hand.

THADDEUS P. CARR.
